BUILDING CONSTRUCTION

Robert L. Davison, New York, N. Y., assignor to
 John B. Pierce Foundation, New York, N. Y., a
 corporation of New York

Application September 3, 1942, Serial No. 457,158

4 Claims. (Cl. 20—2)

This invention relates to improved building construction.

In particular, the invention relates to improvements in building construction pursuant to which structures capable of comfortably housing troops, campers, or the like, may be readily erected, under adverse or hazardous conditions, from standardized panel units made from materials which, under present circumstances, are not of a so-called "critical" nature.

It is an object of the invention to provide means for quickly and readily assembling a building suitable for accommodating a group of persons under conditions to provide for maximum comfort, or to provide for storage of equipment which must be protected from the weather.

It is an object of the invention to provide a building which departs from conventional construction in that there is no break or distinction between the side walls and roof which are formed of continuous elongate sheets of material, erected at the site of installation by arching said sheets into a substantially semi-cylindrical structure suitably supported and secured at its lower marginal edges to a base frame.

It is an object of the invention to provide a building in which the side walls and roof are a continuous structure formed of relatively light weight panels of laminated pulp-board having desired thermal insulation properties, said panels incorporating as an integral part thereof, suitable exterior weather-proofing and interior finish resistant to dampness or condensation.

It is an object of the invention to provide a building in which the flooring material may be the same as the material forming the side-wall-roof structure, whereby to eliminate the necessity of supplying and/or stocking different types of material for the respective purposes.

It is an object of the invention to provide a building which has adequate facilities for ventilation, and which may be appropriately treated to provide a camouflage effect.

It is an object of the invention to provide a building which, because of its contour, does not cast deep shadows, thereby rendering such building or a group of buildings relatively inconspicuous from the air.

It is an object of the invention to provide a building adequately protected against infiltration of rain or wind-driven water or spray, whereby gutters, down spouts, or the like, are unnecessary.

It is an object of the invention to provide a building which is devoid of longitudinal eaves,

thereby eliminating the necessity of providing against the erosive action of water dripping therefrom.

My improved building construction is particularly adaptable for the accommodation of units of soldiers or the like who must be quickly provided with adequate housing of a semi-permanent character.

According to a preferred form of the invention, 10 the building construction comprises the employment of suitable panels of composition board, for example, laminated pulp board, shipped to the site of installation in flat panel form. Preferably, the outer or "weather" surface of each 15 said panel may have a lamination or coating of suitable water-proof material, such as slate-surface asphalt roofing or equivalent, bonded to the panel to make it an integral part thereof.

It has been found, in practice, that panels of 20 8' width, and of such length as to provide a substantially semi-cylindrical structure having an 8' radius as measured from the finished floor line are readily handled by the erection crew.

In erecting the structure, a framework of timbers may be constructed and laid upon the leveled ground; desirably, the marginal timbers are of 25 4" x 4" cross sectional dimension, and intermediate timbers or "floor joists" of conventional 2" x 4" stock.

30 The side-wall-roof panels are suitably bent over temporary forms and overlap the marginal framing timbers along the sides of the structure. A clamping timber confines the side-wall panels against the side timbers of the base, with an intermediate flashing of water-proof roofing material carried below the finished grade and sloping away from the sides of the structure to afford suitable protection against infiltration of water. Said side-roof panels are made secure 35 by means such as lag screws, nails, or the like, driven through clamping timber and the panels into the base timbers.

40 A floor, also of the asphalt roofing provided panel material, is laid directly upon the ground and secured to the marginal timbers and the floor joists; by employing a double thickness of such flooring material, the water-proof surface of the under panel is placed against the ground to protect against moisture, whereas the asphalt surfacing material of the upper floor panel provides a highly wear-resistant and water-proof floor surfacing.

45 Such building may be made as long as is necessary by erecting a succession of such panels, butt-jointed, with exterior and interior battens at the

joints. In such a double batten construction, the exterior batten may be of pulp board material of suitable width, completely encased in water-proof material, and the interior batten or rib may be a hard wood strip, providing structural strength as well as means for attaching lighting fixtures, clothes-hooks, or the like.

Interior partitions, where necessary or desirable, may be erected on vertical studs, with the pulp board material providing a single or double wall, as desired. End walls, provided with doors, windows, and ventilating louvers, are erected from the pulp-board material. A roof overhang, irregularly contoured, improves the camouflage effect.

Further features and advantages are herein-after described.

In the accompanying drawings:

Fig. 1 is a perspective, partly cut away to show interior construction, of a building embodying the present invention and method of construction.

Fig. 2 is a vertical sectional elevation of a portion of the building.

Fig. 3 is a plan view of a base frame suitable for the building.

Fig. 4 is a detail, in sectional elevation, showing the building construction at the lower side margins thereof.

Fig. 5 is similar to Fig. 4, showing a second form of floor construction, in which the flooring is laid upon transverse joists.

Referring to the drawings for a more detailed description of the invention, a base frame 10, Fig. 3, may first be erected and laid directly upon previously leveled ground, being secured thereto by suitable stake anchors. Said frame may comprise side and end marginal timbers 11, 12, respectively. It has been found that timbers 4" x 4" in cross section are adequate for the purpose. Laid transversely, and suitably fastened to the side margin timbers 11, so that the upper surfaces of the respective elements are in alignment, are any desired plurality of transverse members 14, which may be of conventional 2" x 4" stock. Depending upon the total length of the building, or in the further circumstance that interior partitions are provided in the structure, one or more intermediate 4" x 4" transverse timbers 15 may be employed. At the respective corners of such base frame, suitable timber stake anchors 16 may be provided, said stake anchors projecting into the ground for such distance as is required or permitted by the nature of the soil.

The frame timbers and cross members may be laid upon the surface of ground suitably leveled, following which the spaces between the end timbers and the intermediate transverse timbers may be filled with tamped earth.

There is no delineation between the side walls and roof of the structure; a double thickness of laminated pulp board, each thickness of board being approximately one-half inch to render said boards capable of being readily bent into semi-circular formation over suitable temporary frames (not shown), forms a continuous side-wall and roof. The length of the pulp board panels is suitable to provide a semi-cylindrical structure having a maximum height of preferably not less than 8 feet and a 16 foot width.

The respective pulp board sheets, designated 17 for the outer lamination and 17a for the inner lamination, may have bonded to one surface, a weather and wear resistant material; conventional mineral surface asphalt roofing has been

found satisfactory. This surface coating, designated 17 for the outer lamination 17 and 17a for the inner lamination 17a provides a water-proof exterior and an interior which is proof against condensation of moisture on the inner walls of the structure. If desired, however, the interior surface 17a of lamination 17a may be of water-proof paint or wax impregnation, according to choice.

As illustrated, particularly in Fig. 2, the respective pulp board sheets 17 and 17a are staggered, there being suitable overlap between the edges of the respective pulp board laminae.

The pulp board sheets 17, 17', as shown in Fig. 4, suitably overlap the side marginal timbers 11, and are secured thereto by a longitudinal stringer or timber 18 between which and the timbers 11, the panels may be securely clamped as by lag screws 20, nails, or other fastenings, spaced as required.

A suitable water shed along the side walls of the building is provided by a sheet 21 of asphalt roofing or equivalent, inserted between the longitudinal member 18 and the outermost panel 17, and carried downwardly and away from the base structure for a suitable distance to form a flashing to preclude the seepage of water into the ground beneath the base frame.

At the overlapping joints of sheets 17, 17a, and at each end of the structure, it is preferred to use double battens; an outer rib 22 which may be of pulp board material, is completely encased in suitable water-proof material 22'. Internally of the structure, and complementing each exterior rib 22, it is preferable to use a hard wood rib 23 of suitable dimension. A hardwood rib of 4" width and 1/2" thickness will readily conform to the curvature of the wall-roof forming panels. At suitable intervals around the periphery of said double battens, they may be mutually secured by means such as the illustrated bolts 24. The double battens provide stiffening members sufficiently strong to make unnecessary the use of interior framing except at locations where unusually high winds are encountered.

The floor 25 is constructed from similar pulp board materials having the indicated outer laminations of water-proof material. The floor panels may be fastened to the marginal timbers 11, 12 and to the transverse beams 14 by screws or nails, as desired. As appears in Fig. 2, the floor panels are staggered with respect to each other, to form a broken joint to prevent dampness or moisture from working into the interior of the building.

As shown in Fig. 4, the double panels forming the floor 25 are placed back-to-back, so that the exterior surface of each floor panel is of the water-proof material. Mineral-surfaced asphalt roofing, when employed as the exterior surface, provides an excellent wear-resisting surface for the floor, as well as proof against the penetration of dampness into the lamination which is in contact with the ground.

Where floor panels having a width equal to the maximum width of the structure are to be used, as is frequently desirable, it is obvious that said floor panels should be fastened to the foundation frame prior to the erection of the walls.

The end walls 26 of the building are constructed of similar pulp board material of suitable thickness, and in single or double panel, as desired, and are provided with windows 27 and a door 28 suitably framed and supported. Above each of the windows and the door are louvers 30, for ventilation.

tion. The end walls 28 may be secured to any suitable vertical framing or studding (not shown).

A building of any required length may be formed by a mere succession of the wall-roof panels and appropriate floor panels. In buildings of substantial length, wherein it may be desired to sub-divide the structure into a plurality of smaller rooms, vertical partitions 34 of pulp board may be erected upon suitable framing.

At the front and rear walls of the structure, water-proofing may be accomplished by sheets 32 of asphalted sheet or roofing material, suitably carried up over the floor as shown in Fig. 2 and underneath the transverse floor plate 33. A sill 34 may be suitably secured to the transverse frame member 12, and may afford a step or threshold at the door. After the building has been erected, the ground surrounding the same may be graded. The sheets 21 at the sides, and 32 at the ends, of water-proof material together completely encompass the building, and serve adequately to divert rain water, rendering it unnecessary to trench around the building or to provide gutters, leaders, or other conventional means for conveying rain water to a point of collection remote from the building.

In installations where sand or other unstable ground conditions make it impossible or undesirable to erect the building directly upon the ground, an alternate foundation construction, illustrated in Fig. 5, may be employed. Pursuant to such construction, the side and end marginal framing may comprise members 40, 2" x 10" in cross sectional area, or other dimension as required, supported upon, and secured to, piers 43. Secured to the lower marginal edges of the side-framing members 40, are 2 x 4's 41, forming a step upon which to support floor joists 42, preferably 2" x 6", spaced 12" on centers, to which the floor 25 is attached. Other structural details may be as previously set forth, with side wall panels secured to the framing members 40 by means similar to the clamping member-lag screw construction; and flashing 21 at side walls and 32 at end walls likewise employed.

The smooth surfaces of the structure and semi-cylindrical form, make camouflaging particularly effective. Deep shadows are cast only when the sun is very low in the sky, and are quickly obliterated by the dusk of evening or the rising sun of morning. To enhance the camouflage effect, the outer lamination 17 may be carried forward over the end walls, and cut irregularly.

The clean, water-proof interior wall and floor surfaces make it possible to quickly and completely fumigate or decontaminate the structures, a feature of great importance in consideration of the transient occupation to be expected in connection with the normal use of the buildings.

Whereas I have described my invention by reference to specific forms thereof, it will be understood that many changes and modifications may be made provided they do not depart from the scope of the claims.

I claim:

1. A building, including a foundation frame, a combined wall-proof structure formed from superimposed layers of continuous sheet material bent into substantially semi-circular form from

initially flat status and secured to side marginal elements of said foundation frame, said layers of sheet material being offset with respect to their lateral edges, each said layer of sheet material having at least one water-proof surface, a second plurality of layers of said sheet material similarly bent and secured, and arranged with their lateral edges in abutting relation with corresponding layers of said first-named sheet material, whereby the offset relation of the respective sheets provides a broken joint, a batten disposed in contact with the external sheets and covering the joint therebetween, a complementary batten in contact with an internal sheet beneath the external batten, said battens being secured to said sheets and to each other to maintain the semi-circular form thereof, end walls, and end walls completing the closure of the structure.

2. A building, including a rectangular foundation frame, a combined wall-roof structure formed of a plurality of layers of pulp-board sheet material bent at the site of erection into substantially semi-circular form from initially flat status and secured to side marginal elements of said foundation frame, said layers of sheet material being offset with respect to their lateral edges to form a discontinuous joint, a second plurality of layers of said sheet material similarly bent and secured and arranged with their lateral edges in abutting relation with the corresponding layers of said first named sheet material, battens arranged externally of said layers of sheet material at the juncture of successive external sheets, complementary battens disposed internally of the structure, said battens being secured to each other and to said sheet material to support the same in semi-circular formation, and a floor of sheet material substantially identical with said first-named material secured to said foundation frame.

3. A building, comprising a rectangular foundation frame, a combined side-wall-ceiling structure including a wide, initially flat, panel of flexible material bowed at the site of installation into substantially semi-cylindrical form and secured at its ends to opposite sides of the foundation frame, flexible battens bent at the site of installation from initially flat status to conform to the curvature of the said erected panels, said battens being disposed beneath said panels and secured thereto to assist in maintaining the semi-cylindrical form assumed by said panels, and end walls enclosing said structure.

4. The method of building construction which includes the steps of preparing a foundation frame including marginal members and members extending transversely thereacross, placing said foundation frame upon a leveled earth surface, erecting a semi-cylindrical wall-roof structure upon said foundation frame by bowing initially flat panels into semi-circular form and securing their ends to marginal members of said foundation frame, bending initially flat battens to conform to the semi-cylindrical shape assumed by said panels and securing said battens to the underside of said panels, applying flooring directly to said foundation frame, and enclosing said structure by means of end walls.

ROBERT L. DAVISON.
